Patented Oct. 18, 1960

189,076

ORAL BREATH SWEETENER INHALER

Irving Russell Altman, 3411 McPherson,
Fort Worth, Tex.

Filed July 14, 1958, Ser. No. 51,774

Term of patent 14 years

(Cl. D83—1)

FIG. 4

FIG. 1

FIG. 2

FIG. 3

Fig. 1 is a front perspective view of an oral breath sweetener inhaler showing my new design with the cover in open position;

Fig. 2 is a rear perspective view thereof with the cover in closed position;

Fig. 3 is a top plan view thereof with the cover in open position; and

Fig. 4 is a front elevational view thereof with the cover in closed position.

I claim:

The ornamental design for an oral breath sweetener inhaler, as shown.
